CLAIM

The ornamental design for a tire, as shown and described.

DESCRIPTION

FIG. 1 is a top, front, left side perspective view of a tire showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a partially enlarged view of the indicated area "8" in the FIG. 4.

The dot-dash broken lines indicating an enlargement portion of the design form no part of the claimed design.
